(57) **CLAIM**

The ornamental design for a radiator grille for a vehicle, as shown and described.

DESCRIPTION

This application contains subject matter related to the following co-pending U.S. design patent applications:

Application Ser. No. 29/579,108, filed Sep. 28, 2016 and entitled “Radiator Grill for a Vehicle”;

Application Ser. No. 29/594,683, filed herewith and entitled “Vehicle, Toy, and/or Replicas Thereof”; and

Application Ser. No. 29/594,701, filed herewith and entitled “Radiator Grille for a Vehicle”.

FIG. 1 is a front view of a radiator grille for a vehicle according to the design;

FIG. 2 is a right side perspective view thereof;

FIG. 3 is a left side perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.
